UNITED STATES PATENT OFFICE.

HENRY E. MOFFAT, OF HIGHLAND PARK, MICHIGAN, ASSIGNOR OF ONE-SIXTH TO
GEORGE W. MARSHALL, ONE-SIXTH TO GEORGE L. MARSHALL, AND ONE-SIXTH TO
GAYLORD L. MARSHALL, ALL OF DAYTON, OHIO.

FEED-WATER HEATER AND PURIFIER.

Application filed October 31, 1921. Serial No. 511,659.

To all whom it may concern:

Be it known that I, HENRY E. MOFFAT, a subject of the King of Great Britain and Ireland, residing at Highland Park, in the county of Wayne and State of Michigan, have invented certain new and useful Improvements in Feed-Water Heaters and Purifiers, of which the following is a specification, reference being had therein to the accompanying drawings.

This invention relates to feed water heaters and purifiers and the invention consists in the structural features and arrangement of parts hereinafter fully described.

The drawing comprises a view of the invention in sectional elevation.

In said view the reference character 1 designates a cylindrical casing having pipes 2 and 3 communicating with its top and bottom for respectively delivering and discharging exhaust steam, derived from steam driven machinery of any kind. In the lower portion of said casing there is arranged a partition 4 forming with the bottom of the casing the chamber 5 within which is located oil separating means 5^a the details of which do not concern the present invention. A full disclosure of such a means, similar to that shown in the accompanying drawing may be found in applicant's Patent 1,455,348, issued May 15, 1923. Above said chamber are extended the several sections of pipes 6, 7, and 8 which conduct a portion of the purified exhaust steam successively through chambers 6', 7' and 8'. 9 is a cold water supply pipe discharging in the upper portion of the chamber 8'. Below the outlet of said pipe is arranged a perforated deflector 10 which distributes the discharge over a considerable area. Within each of the chambers 7' and 8' there is arranged, surrounding the corresponding exhaust pipe 7 or 8, a filter bed 11 of excelsior or like material, through which the feed water percolates downwardly, depositing its mineral matter and other impurities in said filter bed. The filtering material 11 rests upon a perforated plate 12 and a similar plate surmounts said material. After filtering through the beds 11, the water drops from the lower plates 12 of said beds through the chambers 7' and 6' in the form of a spray or rain. Thus the temperature of the feed water is raised to the boiling

point. Through each filter bed 11 there is extended a vertical by-pass pipe 13 which insures a supply of feed water even if, through neglect or other cause, said beds become solid with mineral matter. Between the sections of pipes 6, 7 and 8, dome shaped deflectors 14 are arranged, which deflect the exhaust steam rising through said pipes laterally into the chambers, 6' and 7'. In escaping from said chambers a portion of the steam rises through the filter beds, the balance entering the exhaust pipe above said deflectors. 15 is a valve in the water supply pipe controlled through a rod 16 by a float 17 within the settling chamber 6', so as to cut off the water supply when there is a predetermined accumulation of water in said chamber 6'. From the oil separating chamber 5 there is provided an auxiliary outlet 18 having branches 18^a, 18^b, and 18^c controlled by valves 19. Such portion of the purified exhaust steam as is not required to heat the feed water may be conducted through said branches to radiators, laundry machines or other apparatus. In one of said branches there is provided a check-valve 19^a adapted to automatically open under atmospheric pressure to break any vacuum forming within the oil separating chamber. The upwardly extending branch 18^a has communication through a pipe 20 controlled by a valve 20^a with the top of the casing 1, the inlet to said pipe being protected by a screen 21 within the casing. A check valve 22 in the pipe 20 serves to break any vacuum forming in the upper portion of the casing. 23 is a valve controlling the flow through the exhaust pipe 6 within the settling chamber 6', a stem 24 being extended to the outside of the casing 1 for control of said valve. The delivery of exhaust steam to the heating chambers 6', 7' and 8' may be so controlled by means of said valve as to establish any desired proportion between the quantities of steam heating the feed water and that supplied through the outlet 18 to the other apparatus. Within the settling chamber 6' a vacuum breaker 25 is arranged with its inlet within the exhaust pipe 6, and is provided with a check valve 25' exteriorly of the casing. 26 is a pipe delivering live steam to the oil separating chamber, 27 is a pipe for delivering hot water from the

lower-most chamber 6' to a boiler feeding pump (not shown) or to any other desired apparatus, and 28 is a pipe taking care of any overflow from the settling chamber 6'.

5 From the preceding description it is believed the operation of the described apparatus will be evident. The filter beds 11 acquire a high temperature from the steam rising therethrough so that said beds are an 10 effective heating medium for the water, as well as a filtering means. The finely divided form in which the water falls through the exhaust steam filling the chambers 6' and 7' is also very conducive to a transfer 15 of heat from the steam to the water.

The provision of the valve 23 in the pipe 6 permits a regulation of the quantity of purified exhaust steam employed for heating the feed water so that a maximum portion 20 of said steam may be diverted through the auxiliary outlet 18 for delivery to other apparatus. Also the provision of said valve is advantageous in permitting a complete shutting off of steam from the chambers 6', 25 7' and 8', when it is desired to clean said chambers or to renew the filter beds.

By locating the outlet end of the vacuum breaking pipe 25 within the exhaust pipe section 6, said end is protected from 30 the rain of feed water and cannot be closed by mineral deposits from said water. Also this location of the outlet of the vacuum breaker insures relief of any vacuum occurring in the pipe 6, before such vacuum can 35 be transmitted to any of the chambers 6', 7' and 8'.

The provision for introducing live steam to the oil separating chamber by way of pipe 26 permits maintaining such pressure 40 as may be requisite for the apparatus served by the pipes 18^a, 18^b, etc. Also the introduction of a limited quantity of live steam to said chamber is of value in preventing the formation of a vacuum.

45 An important feature of the described construction is the absolute prevention of any oil becoming mixed with the boiler feed water. It is well known that the presence of oil in the boiler is extremely detrimental 50 to the operation of the same. The presence of oil results in a foaming of the water and also the oil tends to collect or accumulate as a scum all mineral and metallic matter with which the water may be charged.

55 When the oil and accumulated matter become heavier than the water they sink from the surface and form a scale on the shell or tubes within reach of the fire line. This scale excludes the water from contact with the boiler plates and tubes and enables the fire to burn and destroy them.

In the majority of plants using steam driven machinery, the exhaust steam is discharged, either without utilization of any 60 of the heating properties of said steam, or

there is utilized only a small proportion of the exhaust for heating the boiler feed water. An important economical feature of the herein described apparatus is the feasibility of utilizing substantially the entire 70 heating value of the exhaust. Also said apparatus permits of varying the pressures or head at which the exhaust steam is utilized in various heaters or other devices. Thus for example it is desirable to deliver the steam at a considerable lower pressure to heating apparatus above the level of the steam purifying chamber 5 than to such apparatus at a lower level than said chamber. A proper relative adjustment of the valves 75 19 and 23 will secure the desired differential pressures.

It is further to be observed that the invention as compared to prior apparatus, materially reduces the trouble resulting from 80 creation of vacuums in the casing 1, since the steam supply to the water heater is minimized. The pipe 20 provides an exhaust steam exit from the chamber 8' when the back pressure valve is adjusted to remain 85 closed.

What I claim as my inventions is:

1. In a feed water heater and purifier, the combination with a casing, of a filter bed 90 therein, exhaust steam chambers being formed above and below said filter bed, an exhaust steam pipe extending through said filter bed and communicating with said chambers, a cold water supply pipe discharging within said casing above said filter bed, an oil separating chamber having a main outlet to said exhaust steam pipe and having an auxiliary outlet, an exhaust steam supply connection to the oil separating 95 chamber and means for variably proportioning the exhaust steam delivery from the oil separating chamber to said main and auxiliary outlets.

2. In a feed water heater and purifier, the combination with a casing, of a filter bed 100 therein, exhaust steam chambers being formed above and below said filter bed, a cold water supply pipe discharging within said casing above said filter bed, an exhaust steam pipe extending through said filter bed 105 having connection with said exhaust steam chambers, an oil separating chamber having a main outlet to said exhaust steam pipe and having an auxiliary outlet, a valve in said exhaust steam pipe for variably proportioning the flow through said main and auxiliary outlets, and control means for said valve extending exteriorly of said casing.

3. In a feed water heater and purifier, the combination with a casing, of a filter bed 120 therein, exhaust steam chambers being formed above and below said filter bed, a cold water supply pipe discharging within said casing, above said filter bed, an oil separating chamber, means for delivering 125

130

exhaust steam to said exhaust steam chambers from the oil separating chamber, an auxiliary discharge connection leading from said oil separating chamber, and means for 5 variably proportioning the exhaust steam delivery from the oil separating chamber to said exhaust steam chambers and to said auxiliary connection.

4. In a feed water heater and purifier, the 10 combination with a casing, of a filter bed therein, a cold water supply pipe discharging within said casing above said filter bed, an exhaust steam pipe extending through said filter bed and having communication 15 with exhaust steam chambers formed above and below said filter bed, an oil separating chamber having a main outlet to said exhaust steam pipe, and a vacuum breaker opening into said exhaust steam pipe and 20 having its inlet outside of the casing.

5. In a feed water heater and purifier, the combination with a casing and a filter bed therein, exhaust steam chambers being formed above and below said filter bed, a 25 cold water supply pipe discharging within said casing above said filter bed, an exhaust steam pipe extending through said filter bed, and opening into said exhaust steam chambers, an oil separating chamber having an 30 exhaust steam inlet and having an outlet to said pipe, and a vacuum breaker having a down turned outlet within said exhaust steam pipe and having an inlet outside of said casing.

35 6. In a feed water heater and purifier, the combination with a casing and a filter bed therein, exhaust steam chambers being formed above and below said filter bed, a cold water supply pipe discharging within 40 said casing above said filter bed, an exhaust steam pipe extending through said filter bed and connecting with said exhaust steam chambers, an oil separating chamber having a main outlet to said exhaust steam pipe and 45 having an auxiliary outlet and a pipe communicating with said auxiliary outlet having connection with the top of the casing.

50 7. In a feed water heater and purifier, the combination with a casing and a filter bed therein, exhaust steam chambers being

formed above and below said filter bed, a cold water supply pipe discharging within 55 said casing above said filter bed, an oil separating chamber, means for delivering the exhaust steam to said exhaust steam chambers from said oil separating chambers, an auxiliary heating pipe leading from said oil separating chamber, a connection from said auxiliary pipe to the upper portion of the casing, and a check valve in said connection, opening under atmospheric pressure 60 upon a predetermined pressure drop within the casing.

8. In a feed water heater and purifier, the combination with a casing and a filter bed therein, heating chambers being formed above and below said bed, a cold water supply pipe discharging within said casing above said filter bed, an oil separating 70 chamber, means for successively flowing exhaust steam through said oil separating chamber and heating chambers, an auxiliary exhaust steam discharge pipe leading from said oil separating chamber, a connection from said pipe opening into the upper portion 75 of said casing, and a screen within the casing protecting said opening.

9. In a device of the character described, the combination with an exhaust steam purifying chamber having a plurality of 80 outlets of a water heater, a pipe leading from said chamber to said heater, a valve controlling said pipe and a pipe leading from another outlet of said chamber for delivering steam to auxiliary apparatus. 85

10. In a feed water heater and purifier, a casing, steam purifying means within said casing, a feed water heater within said casing, a pipe within said casing for delivering steam from the purifying means to said 90 water heater, a valve within said casing controlling said pipe, and control means for the valve extending exteriorly of said casing.

11. In a device of the character described, the combination with a steam purifier and a water heater, of a pipe delivering steam from a purifier to the heater, and a vacuum breaker having its outlet within said pipe. 95

In testimony whereof I affix my signature.

HENRY E. MOFFAT.
